STEAM SHOWER FOR PAPER CORRUGATORS

Thomas S. Fitchett, Glen Arm, Md., assignor to
 F. X. Hooper Company, Inc., Glen Arm, Md., a
 corporation of Maryland

Application July 28, 1937, Serial No. 156,084

2 Claims. (Cl. 154—30)

In the manufacture of single-faced corrugated board to be used as such or to be further faced on the uncovered side of the corrugated material to form double-faced corrugated board, it is usual to soften the straw, which is the term applied in the art to the paper which is to be corrugated, by steaming it as it enters the corrugating machine.

The steaming device usually extends across the path of the web above and below the web at the rear of the machine, and as the corrugated board is made in a variety of widths there is generally some means for confining the delivery of steam to the width of the web. This steaming apparatus, which has been variously referred to in the art as a "steamer," a "pre-heater," or a "steam shower," has been provided in various forms. In one instance, it is in the form of a row of nozzles mounted on and fed by a transverse pipe on one or both sides of the web; and, in order to limit the delivery of steam to the width of the web or to otherwise regulate the supply of steam, each nozzle has been provided with a valve, the valve being opened or closed to regulate the steam discharge to the width of the web.

This type of steam shower is comparatively expensive to construct, cumbersome, and slow in regulation, and presents the difficulty that the discharge of steam is not confined to the paper or straw, there being in the majority of instances a considerable opportunity for the escape of the steam into the room where the machine is located, with consequent inconvenience and discomfort to the workmen and expense incident to the waste of steam.

The primary objects of the invention are to provide a steam shower for paper corrugating machines which is cheap to construct, one in which the adjustment of the area of the discharged steam to the width of the straw or paper to be treated is easily and quickly performed with a high degree of accuracy, and one in which the discharge of steam into the room is reduced to the minimum or practically eliminated. The steaming device shown may be used for treating similar webs with fluids other than steam.

In the accompanying drawings, I have illustrated a steam shower for the purpose described, embodying the features of the invention in a preferred and modified form, together with so much of a corrugator equipped with the usual mechanism for applying a single facing as is necessary to a full understanding of the invention.

In the drawings:

Figure 1 is a side elevation of the steam shower shown in connection with a single facer corrugating machine, the machine being broken away to show the rolls of the corrugating machine and facer in section, the arrangement being conventional.

Figure 2 is an elevation showing two steam shower members, one above and one below the web, brackets supporting the same being shown in section on a vertical plane 2—2 in Figure 1, 10 the tubular body members of the respective steam showers being arranged in the broken line position in Figure 1, the full line position being the preferred arrangement, and the tubular body members being thrown out of horizontal alignment by adjustment from the full line position in Figure 1 for convenience of illustration, the position Fig. 2 being also an operative position.

Figure 3 is a section on the line 3—3 in Figure 2 looking in the direction of the arrows, portions of 20 the bottom tubular body member being broken away for convenience of illustration.

Figure 4 is a side elevation of a modified form of steam shower tubular body member, showing a different method of adjusting the length of the 25 line of steam discharge to the width and position of the web. It is adapted for use on both sides of the web, as is the first form.

Figure 5 is a section on the line 5—5 in Figure 4.

Figure 6 is a top plan view of the structure of Figures 5 and 6.

Figure 7 is a detailed view of the slot-closing member.

Referring to the drawings by numerals, each 35 of which is used to indicate the same or similar parts in the different figures, the construction shown in Figure 1 comprises a side frame member 1 on the right of the machine the front of the machine being treated as at the right in 40 Figure 1, and a fragment of a side frame 2 on the left side of the machine and toward the observer. This is broken away along the line a in said figure, showing the steam shower in elevation and the rolls of the corrugating machine 45 in section.

The illustration includes upper and lower corrugating rolls 3 and 4 which are made hollow to provide for heating and are provided with longitudinally extending inter-meshing teeth 5 50 for the corrugating operation, and strippers 5', all in accordance with the usual practice. The machine also includes heater rolls 6 and 7 for presenting and preheating the facing web 8 which is passed around these rolls and then

around the heater and presser roll 9 in contact with the corrugated straw, as the material used for this purpose is called. The straw web, indicated by reference character 10, is fed to the machine from the rear or left in Figure 1 through the steam shower 11, to be later described, passing over and about the upper corrugator roll 3 and then backwardly between the corrugator rolls 3 and 4 where the corrugating operation 10 is performed.

After the corrugating operation, the web, which moves in left-handed rotation about the lower corrugator roll 4, passes in contact with the pasting roll 12 which is supplied with adhesive by means of the roll 14 which rotates in the paste pot or trough 15 and in contact with the roll 12.

The straw web 10, as aforesaid, is steamed and pre-heated and thus softened as it is fed to the machine through the steam shower apparatus 11 20 at the rear or upper left in Figure 1.

The steam shower, as shown, consists of one or two or any suitable number of tubular steam shower members, two being shown at 20 and 21. These appear in end elevation in Figure 1, being 25 arranged transversely of the path of the web 10 and each being of a length somewhat in excess of the width of the widest web to be treated and the corrugated board to be produced in the machine. In the arrangement shown, the tubular 30 steam shower member 20 is below the web and the corresponding member 21 is above the web, the steam from the member 20 being discharged upwardly and from the member 21 downwardly in contact with the web as hereinafter described.

35 The shower member 21 is mounted on brackets 16 supporting the tubular shower member 21 at each end, and the member 20 is supported on brackets 17 likewise at each end. The brackets 16 are secured to the side frames 1 and 2 by means of bolts 22 in slots 24, and the brackets 17 are secured to the brackets 16 by bolts 25 in slots 26, so that both of the tubular shower members 20 and 21 are adjustable up and down relatively to the frame and relatively to each other to provide for the treatment of the web 10 either in the flat condition as illustrated in Figures 2 and 3 or with the web deflected about the tubular body members, which is the preferred arrangement, as shown in Figure 1; i. e., in the full line 50 positions.

Having particular reference to the construction shown in Figures 2 and 3, the tubular shower members 20 and 21 are shown each in the form of an ordinary cylindrical pipe, the size shown being approximately 3" in diameter. The shape of the cross section and the size of the pipe are not of great importance except that a chamber within the tubular members 20 and 21 sufficient to permit expansion of the steam as fed is desirable. These tubular shower members are closed at their opposite ends by means of plugs 27 and 28 as to the tube or pipe 20, and 29 and 30 as to the pipe 21, one or both the plugs in each tubular member or pipe being preferably removable. 60 They may be secured by set screws 23. Each tubular shower member 20 and 21 is shown as provided with a pair of pistons 31 and 32 slidably mounted therein and preferably provided with suitable packing rings 33 or other suitable 65 means for preventing the steam from passing the pistons.

In the form shown in Figure 2, the pistons are moved oppositely simultaneously and uniformly by means of a right and left-handed screws 34, 70 which screws have suitably reduced shanks 35 at

each end, and each is provided with a rotating bearing in the end plugs 27-28, etc., being supported against longitudinal motion by thrust means, as collars 36 secured by pins 36' on the outside and a shoulder 37 on the inside.

5 The brackets 16 and 17 are shown as provided with suitable bosses at 38 which, as shown, are bored at 39 or otherwise provided with suitable seats for the ends of the tubular shower members 20 and 21; and the shanks or shafts 35 are provided with square, protruding ends at 40 for engagement by a suitable wrench or crank for adjustment of the pistons.

Any suitable discharge means may be provided, arranged transversely of the web, adapted to distribute steam to the web across its entire width, 15 and having a plain surface surrounding the discharge area and contacting the web. For this purpose, the bottom tubular shower member 20 is shown as slotted longitudinally at the top at 41 in substantial parallelism with the axis for a length corresponding to the full width of the maximum web to be treated, and the tubular member 21 is shown as correspondingly slotted as to its bottom surface at 42. The edge portions 25 42' on each side of the slots 41 present a surface of greater or less width in contact with the web across its transverse dimension.

Steam is introduced preferably near the center of each body member by means of suitable pipes 30 43-44, and the bottom tubular shower member 20 is shown as provided with a discharge pipe 45 for condensed water, though little difficulty is encountered from condensation.

The details shown are illustrative of the application of the principles of the invention and subject to variation of design, any type of openings adapted to distribute the steam across the width of the web and having their edges in closed contact with the web may be substituted 40 for the longitudinal slots shown, and the term "piston" is intended to apply to any movable closing means for limiting the discharge to the width of the web; and any means for moving and adjusting the pistons may be substituted for 45 the screws shown.

Figures 4, 5, and 6 illustrate a tubular steam shower member 50 having a different type of adjustment whereby the pistons 51 and 52 are independently adjustable not only to the width but 50 to the path of the web, whether it be at the center or at either side of the machine, it being understood that any convenient type of guiding means may be provided in connection with either or both steam showers for determining the position of the web as it passes through the shower.

For this purpose, guide members 53, which are shown as T-shaped, having their shanks seated in the respective pistons 51 or 52 and projecting through the steam discharge slots 54, may be 60 employed. The cross arms of the T member 53 lie at the sides of the web above or below the tubular shower member, being of sufficient height or thickness and curved at their edges 55 disposed toward the paper to act as edge guides.

The piston and guide are shown fragmentarily in Figure 7, the shank of the T guide being indicated by reference character 57 and the cross bar of the T by reference character 58. The guide portions or cross bars 58 may be omitted, 70 and the slot-closing shanks 57 are also regarded as a refinement.

The ends of the tubular shower member 50 are closed at 60 in any suitable manner, and any means for moving the pistons to be described 75

may be used, the screw arrangement shown being preferred.

The important feature of this form of the invention, as already suggested, is the provision of two adjusting means, shown in the form of screws 61, for the piston 51, and 62 for the piston 52, whereby the pistons are adjusted to conform to the position as well as the width of the web. The adjusting screw 61 for the piston 51 is threaded at 63 from the corresponding or left end of the cylinder adjacent the plug 60 to a point near the center, the screw shaft at 64, where it extends through the piston 52 by way of opening 65 being plain, preferably forming a substantially steam-tight bearing. The screw 62 is similarly threaded at the right at 66 from the plug 60 and up to a point near the center of the length of the tubular member 50, each screw having a threaded engagement with the corresponding piston and extending freely through the other piston.

The shaft of the screw 62 at 67, as in the case of screw 61 at 64, is plain and extends through an opening 68 in the piston 51 which it fits sufficiently to substantially prevent the passage of steam, packing being used in both instances if desired. Both screws are shown as having reduced shanks at their ends at 69 which run in bearings 70 in the plugs 60, the thrust being taken up as in the previous instance, i. e., as shown and described in connection with Figure 2, or in any suitable manner; and both of the shanks 69 should have square or angular ends 71 for engagement by a crank or wrench.

In Figure 5, the tubular steam shower member 50 is shown in operative relation to a web 72 of straw or similar material, it being understood that two tubular shower members are ordinarily used in the cooperative relation shown in Figures 1, 2, and 3. Figure 2 also shows the web 72 deflected downwardly on both sides of the slot 54, this illustration being in broken lines and corresponding with the full line arrangement in Figure 1. In this way, more complete closing of the slot 54 may be obtained with a more efficient operation in the way of economy and prevention of the escape of steam.

Many changes of form and arrangement and construction are contemplated in connection with both embodiments of the invention.

In operation, the straw web 10 is laid over and under the steam shower body members 20 and 21, covering the slots or other steam discharge means 41 and 42 therein, as shown in Figure 1 and also in Figures 3 and 5, from which point it is laid over the upper corrugating roll 3 extending downwardly about the same to the right in Figure 1 and then to the left beneath the bottom of the roll 3 and between corrugating rolls 3 and 4 and around the roll 4 in left-handed rotation after corrugation where it passes in operative relation to the pasting roll 12. The facer web 8 is introduced from a suitable supply roll and fed over the guide roll 75 to the heater roll 6, around which it is passed in left-handed rotation, being likewise passed in left-handed rotation about the heater roll 7 and then about the heater and presser roll 9 which presses it in contact with the paste-covered corrugated web 10 on roll 4, the single-faced corrugated board being discharged from the machine as indicated at 74.

Prior to the threading of each new web of a new width through the machine, the pistons 31-32 or 51-52 are adjusted to the width of the web. In this connection, it will be understood

that the pistons in Figure 2 are adjusted uniformly and simultaneously toward and from the center to the width of the web, whereas the pistons 51 and 52 (Figures 4, 5, and 6) are adjustable independently so that they can be accommodated not only to the width of the web but to any path which may be selected for passing it through the machine, the same not necessarily being on center.

The guides 53 shown in Figures 4, 6, and 7 at 10 the sides of the web and having their shanks 57 of the width of the slot 52 extending through the same, give additional protection against the possibility of the loss of steam, and may be arranged as shown to serve as guides for the side edges of the straw or paper. They also serve to indicate the position of the pistons.

It will be understood that in the operation of the machine, the pistons being adjusted to the width and location of the web, steam, being introduced by way of the pipes 43 and 44, is discharged from the portion of the slot or other discharge means 41-42 or 54 between the pistons and thus confined to the width of the web which overlies and substantially closes the slot, so that all or practically all of the steam discharged is applied directly to the web which is thus pre-heated, steamed, and softened prior to its presentation to the corrugator rolls. Escape of steam is practically eliminated by the close contact of the web with the tubular members or other edges of the slots or discharge openings and adjustment is easily and quickly performed. It is understood that the adjustment is a single one for each member or at least a single adjustment for each position, greatly simplifying the adjustment and the chances of an oversight.

I have thus described a preferred and modified form of the invention, the description being specific and in detail in order that the manner of constructing, applying, operating, and using the invention may be fully understood; however, the specific terms herein are used descriptively rather than in a limiting sense, the scope of the invention being defined in the claims.

What I claim as new and desire to secure by Letters Patent is:

1. A steam shower for web paper corrugators comprising an elongated steam chamber extending transversely across the path of the web and in contact therewith, said chamber having a narrow slot extending along the portion over which the said web passes, means located substantially centrally of the chamber for introducing steam thereto, a pair of adjustable pistons, 55 one of said pistons being located adjacent each end of the chamber and adapted to slide therein for adjusting the length of the slot through which the steam passes and an adjusting screw for each of said pistons passing through the chamber and 60 rotatably supported in both ends of the latter, there being a pair of apertures located in each piston, one aperture being threadably engaged with one of said screws, the other screw being slidably received within the other aperture for 65 supporting said pistons against rotation, each of the said screws being adapted to be rotated from either end of the chamber for actuating the said pistons.

2. A steam shower for web paper corrugators, 70 comprising an elongated steam chamber extending transversely across the path of the web and in contact therewith, said chamber having a narrow slot extending along the portion over which the said web passes, means substantially central- 75

ly located of the said chamber for introducing steam thereto, a pair of adjustable pistons, one of said pistons being located adjacent each end of the said chamber and adapted to slide therein for adjusting the length of the slot through which the steam passes and an adjusting rod thread-

ably engaging said pistons and rotatably supported in both ends of the said chamber, said rod being operable from either end of the said chamber for moving the said pistons relative thereto.

THOMAS S. FITCHETT.
